UNITED STATES PATENT OFFICE.

ABRAHAM SCHOCKET, OF NEW YORK, N. Y.

DESIGN FOR A VANITY CASE.

Application filed February 20, 1922. Serial No. 785. Term of patent 3½ years.

To all whom it may concern:

Be it known that I, ABRAHAM SCHOCKET, a citizen of the United States, residing at New York city, in the county of New York and State of New York, have invented a new, original, and ornamental Design for a Vanity Case, of which the following is a specification, reference being had to the accompanying drawing, forming part thereof.

In the drawings:—

I claim:—

The ornamental design for a vanity case.

ABRAHAM SCHOCKET.
